G. DOBMEIER

SAFETY BUNG

Filed Jan. 5, 1925

Inventor,
George Dobmeier,
by George Geiger
Attorneys.

UNITED STATES PATENT OFFICE.

GEORGE DOBMEIER, OF BUFFALO, NEW YORK.

SAFETY BUNG.

Application filed January 5, 1925. Serial No. 499.

To all whom it may concern:

Be it known that I, GEORGE DOBMEIER, a citizen of the United States, residing at Buffalo, in the county of Erie and State of New York, have invented new and useful Improvements in Safety Bungs, of which the following is a specification.

This invention relates to improvements in the safety bungs used in connection with 10 wine barrels, casks, and the like.

One of its objects is to provide a simple, compact and inexpensive bung of this character which will automatically relieve excess pressure in the barrel or cask and prevent 15 the same from bursting.

Another object of the invention is to provide the bung with reliable and convenient means for detachably retaining the relief valve in place.

20 In the accompanying drawings:—

Figure 1 is a perspective view of a safety bung embodying my improvements. Figure 2 is a vertical section thereof. Figure 3 is a top plan view of the same with the retaining yoke removed. Figure 4 is a detached perspective view of the retaining yoke.

Similar characters of reference indicate corresponding parts throughout the several views.

30 The body 10 of the bung is of the usual tapered form so that when driven into the bung hole 11 of the barrel 12, it will be held therein by friction. Extending axially through the bung-body is a passage 13 having an upwardly-facing valve-seat 14 near its upper end. A ball valve 15 is preferably arranged in this passage and adapted for movement toward the seat for controlling the relief passage of the bung. This valve 35 is normally held against its seat by a spring 16 located in the enlarged outer end of said passage and bearing at its inner end against the outer side of the valve, while its outer end bears against a retaining member or 40 yoke 17 which is constructed to detachably interlock with the upper end of the bung-body.

The retaining member or yoke preferably 45 consists of a disk-like central portion 18 having a vent or perforation 19 therein in line with the bung-passage 13 and a pair of oppositely-extending arms 20 radiating from the central portion and terminating at their outer or free ends in downwardly and inwardly bent locking lips or hooks 21. For the purpose of receiving this retaining yoke,

the top of the bung-body 10, together with the adjoining sides thereof, is provided with a transverse groove or recess 22, those parts of the latter in which the yoke-arms 20 and its hooked-fastenings are arranged being of sufficient width, as shown, to permit a turning or shifting of the yoke to either its locked or unlocked position. The locking lips 21 of the yoke are adapted to releasably engage 50 downwardly-facing shoulders 23 formed in diametrically opposite sides of the bung-body and in line with its recess 22. To release the retaining yoke, the same is turned into alignment with recesses or notches 24 located at one side of the locking shoulders 23 and of the proper depth to permit the displacement of the hooked ends 21 of said yoke when it is lifted from the bung-body.

By seating the arms 20 and the depending 55 hooks 21 of the yoke in the groove 22 of the bung-body, there are no projecting parts of any kind liable to catch on one's clothing or otherwise interfere with persons working around the barrels or casks equipped 60 with the improved bung.

As a whole, this bung is manifestly simple in construction, its valve can be readily and conveniently applied and removed, and no 65 separate fastenings or tools are required for effecting such application and removal.

The bung-body is preferably made of rubber, but it may be constructed of any other suitable material.

I claim as my invention:—

1. A safety bung of the character described, comprising a body adapted to be placed in a bung-hole and provided with a longitudinal passage containing a valve-seat and at opposite sides of its large end with locking shoulders, a valve arranged in said passage and engaging said seat, a removable yoke extending across the large end of said body and provided with end-fastenings interlocking with said shoulders, and a spring 90 in said passage interposed between said valve and said yoke.

2. A safety bung of the character described, comprising a body adapted to be placed in a bung-hole and provided with a longitudinal passage containing a valve seat and at opposite sides of its large end with locking shoulders, a valve applied to said seat, a removable retaining yoke extending across the large end of said body and having oppositely-extending arms terminating in hooked-ends which interlock with said 105 110

locking shoulders, said body having recesses at one side of said shoulders for the passage of said hooked ends, and a spring in said passage interposed between said valve and said yoke.

3. A safety bung of the character described, comprising a body adapted to be placed in a bung-hole and provided with a longitudinal passage containing a valve-seat, a valve applied to said seat, a rotatable retaining member applied to said body and including a vented central portion substantially in line with said body-passage and oppositely-extending arms radiating from said central portion and terminating at their free ends in downwardly and inwardly-turned locking lips, the bung-body being provided at opposite sides with downwardly-facing locking shoulders for the passage of the lips, and a spring in said passage interposed between said valve and the vented central portion of said yoke.

4. A safety bung of the character described, comprising a body adapted to be placed in a bung-hole and having a longitudinal passage and a transverse recess in its top and adjoining sides, a valve applied to said seat, a retaining member arranged in the transverse recess of the bung-body and including a perforated central portion and oppositely-extending arms terminating at their outer ends in inwardly-turned locking lips, the bung-body being provided at its sides with downwardly-facing locking shoulders in line with its transverse recess for receiving said lips, and upright recesses at one side of said locking shoulders for the passage of the lips, those portions of the transverse body-recess containing the arms of said retaining member being wider than said arms to permit rotation of the retaining member, and a spring in said passage interposed between said valve and the central portion of said retaining member.

GEORGE DOBMEIER.
